UNITED STATES PATENT OFFICE.

EDWARD A. ROBINSON, OF MONTREAL, QUEBEC, CANADA, ASSIGNOR OF ONE-HALF TO HIMSELF AND ONE-HALF TO ELLISON EDWARD WORKMAN, BOTH OF MONTREAL, CANADA.

CONNECTER-HEAD SUPPORT.

Application filed December 17, 1921. Serial No. 522,983.

To all whom it may concern:

Be it known that I, EDWARD A. ROBINSON, a citizen of the United States, residing at Montreal, Province of Quebec, Canada, have 5 invented a certain new and useful Connector-Head Support, of which the following is a specification.

My invention relates to connecters intended to join the several pipes of a train system automatically as the cars come together and couple.

The purpose of my invention is to provide separate spring support for the upper and lower portions of the head.

15 A further purpose is to give each separate spring support independent rocking connection with the head.

20 A further purpose is to provide adjustment of the plane at the head by separate projection or retraction of the top and of the bottom of the head.

25 A further purpose is to provide universal joints at top and bottom of the head that the rocking of the head during service may not break contact between parts of the head and the adjoining head.

30 A further purpose is to reduce shock and strain on the head by dividing these shocks and strains at each spring support between two springs and by partially relieving strains at each of these supports by a rocking and slideable joint.

35 Further purposes will appear in the specification and in the claims.

40 I have preferred to illustrate my invention by one form only, selecting the form with a view to its value in illustration of the principles of my invention.

Figure 1 is side elevation of a connecter embodying my invention.

Figure 2 is a broken rear end elevation of the structure seen in Figure 1, showing the connection of the springs with the bracket.

45 Figure 3 is a broken top plan view of the structure seen in Figure 1.

Figure 4 is a fragmentary perspective of a portion of the structure of the head seen in Figure 1.

50 Figure 5 is a broken side elevation of a modified form.

Figure 6 is a section upon line 6—6 of Figure 5.

In automatic connecters it is advantageous to support the connecter separately at the 55 top and at the bottom. I have accomplished this by giving spring support separately to the top and bottom of the head in a head which is supported wholly by springs.

At the same time I have accommodated the 60 vertical and lateral rocking of the head by providing a rocking or rolling and sliding joint between each spring support and the head.

65 Describing the structure shown in Figures 1 to 4, by way of illustration and not in limitation:—

The bracket 10, in rigid connection with the car, carries spring supporting clamps 11 and 12. These clamps are duplicates and 70 are split at 13 to permit insertion of the springs 14 and 15. They are threaded to correspond approximately with the spirals of the springs and clamp by reason of the friction against the exteriors of the springs. I 75 recognize that the character of the clamp here is not material provided it be some device whereby the spring may be rigidly held at one or other end. The clamp is tightened to fix the spring in position. Adjustment of the spring is permitted by changing the length by the distance between adjoining turns, threading it longitudinally through the clamp with the clamp loosened.

80 The two springs 14 and 15 extend forwardly and support two head carriers 16 and 17. As shown in Figure 3 these head carriers have similar reversely directed arms 18 and 19 which branch at 20 into forwardly projected substantially parallel 90 yokes having opposite sides 21, 22 respectively connected by terminals 23, 24. These terminals mate and cooperate with reversely shaped surfaces 25, 26 upon the rear of the head 27 to form sliding, rocking or universal joints between the carriers and the heads.

These cooperating joint members may be of such wedge-shaped, conical or curved section upon their meeting faces as best suits the particular purpose in mind. Thus in Figure 1 a V-shaped wedge is shown, which, however, may be conical where sliding and retraction from tilting in any direction is contemplated. Vertical or horizontal sliding or tilting movements alone would be 100 useful where, as permissible under my in-

vention, the arms 18 and 19 connect with a single clamp such as 16 or 17 united with a bracket by a single spring, or with any other construction in which the arms 18 and 19 are rigid with each other.

Where various tilting and rocking movements are to be accommodated to give as great flexibility as possible with some sliding of the parts, spherical or cylindrical contours also can be used, as in Figure 5, for the two connections from arms 18' and 19' to the head. The forms shown in Figures 1 and 5 are both better suited to and give much better results with relative movement of the arms 19 and 20, and particularly with independent spring support of these arms than where the arms are rigid with each other, as would be the case if united to a single clamp limiting the advantage to sliding movement or to sliding and tilting with respect to the plane uniting the joints.

Either of the parts of the pair may carry the projection and the other the recess, and the space for the joint may be secured by different formations of the head or by side extension of the head at 28', 29' (Figure 6), if desired, instead of by the end extensions of 28 and 29 shown.

In Figures 1 and 5 the head 30 is intended to be shown generically. It carries any suitable ears 31 and tube and gasket construction for uniting the several fluid conduits of one car with those of another. These tubes I have shown generically at 32 as suitable for passenger traffic. If used for freight traffic there will probably be but one or two of these fluid conduits.

The wedge form of universal joint is best illustrated in Figures 3 and 4 where the head extension 28 or 29 and carrier terminals 23 and 24 are resiliently held together by the bolt 33 and spring 34. The bolt fits loosely through the terminal and passes through the preferably conical spring 34 to a combined nut and washer 36 thus pressing together the two parts of the joint. The spring 34 fits in a recess 37 in the terminal to maintain this end in place. Relative tilting or sliding between the parts of the joint is provided for by a temporary yielding in the spring and by the loose fit of the bolt within the terminal.

Where one direction only of yield is desired—vertical in Figure 1, the V-shaped wedges will serve as they will slide for actual vertical movement between them and will rock about the edges of the terminal in response to tilting strains in either vertical or horizontal planes. However the retractive operation of the wedge acts across the wedge only. I appreciate that with very much less advantage these members may be flat, and not wedge shaped, spherical or conical, return to normal position when de-

flecting strain ceases being brought about by the bolt 33 and spring 34 above. Continuous jars of service will aid in overcoming friction between the flat surfaces and will automatically center the parts to normal position.

With tapered, conical, or spherical forms alike, the surfaces defining the side walls of the recess become wedges, such as 38 and 39 (Figure 4), on which the mating side walls of the projection will slide to relieve any serious lateral strain upon the head. This will cause the wedge surfaces of the projection, such as 40 or 41 with the construction seen in Figure 4, or any part of the conical or spherical surface, under like circumstances, to climb the wedge face of the recess permitting shifting of the head as well as separating the parts longitudinally of the bolt.

When the parts are in normal position, tilting can take place between the individual terminals 23, 24 and the head about the limiting edges of the terminals. Where these limiting edges are rectangular, as represented by the edges 42 and 43 in Figure 4 and by the edges parallel to them, the tendency will be to tilt about one or other of these edges.

Though circular edges within the plane of the edges 42 and 43 would give ready tilting without regard to the direction of strain, I prefer the rectangular shape for these terminals because the strains chiefly to be accommodated are in vertical and horizontal planes.

It will be evident that tilting of the terminals in the direction of any given vertical or side movement of the head, such as tilting about the upper edges of the terminals after upward sliding vertical movement of the head, takes place about a shorter radius than when the parts are in the position shown in Figure 1. This is true because that wedge "element," parallel to the apex of the wedge, passing through some such point as 41' would then be resting against the upper limiting edge 44 of the wedge seat and the lines of engagement, both in the head and in the terminal would lie closer to the bolt than with the position of the parts as shown in Figure 1.

The split clamps 12' of the carriers 16 and 17 are like the clamps at 11 and 12. In Figure 1 the bolt lugs of 11 and 12 are shown horizontal while those of 16 and 17 are shown vertical. Other means than threaded split clamps might be used, and other forms of resilient support for the carriers can be used to provide for independence of movement.

In operation, the ears of the head interfit with corresponding ears on the head of a connector upon an adjoining car, making gasketed union between the fluid conduits,

each head being pressed backward by engagement with its fellow. Strains due to vertical and lateral lack of alignment are relieved partially by the joints between the 5 heads and the carriers where both rocking and sliding movements can take place.

In the form shown in Figures 5 and 6 the two carriers 16' and 17' are rigid with arms 18' and 19' respectively but these arms are 10 not divided as in the preceding form. At their ends the arms support laterally extending terminals 23' and 24' which coact with extensions 28' and 29' respectively at the sides of the heads.

15 It will be noted from the illustration in Figures 5 that the engaging surfaces of the members are spherical, an arc of the sphere being seen in curved line 45, as distinguished from the triangular engagement shown in 20 Figure 1. Evidently various forms of construction could be made to carry out the purpose here as in other parts of the invention. Where but one carrier is to be used to support both arms of this figure the 25 surfaces would be wedges or cylinders.

From my description various forms of the invention will be obvious to those skilled in the art, to suit particular installations or the preference of the designer and; it 30 is my purpose to include herein all such variations in character and form as may come within the reasonable spirit and scope of my invention.

Having thus described my invention what 35 I claim as new and desire to secure by Letters Patent is:—

1. In an automatic train pipe connector, a head, a carrier therefor, a V-and-wedge joint between the head and carrier, a tie-bolt therethrough, and a spring surrounding 40 the bolt and thereby held to the head and pressing the head and carrier together at the joint.

2. In an automatic connector, a head bracket adapted for engagement with a fixed 45 train part and having a pair of securing devices connected therewith, springs fastened to said securing devices, a pair of carriers, one secured to the end of each of said 50 springs, a head supported by the carriers and movable connection between each of said carriers and the head.

3. In a train pipe connector a bracket secured to a fixed train part and having two 55 attaching devices thereon, a pair of springs, one secured by each of said attaching devices, a pair of carriers, one mounted upon each of said springs at the opposite end thereof, a head supported by the said carriers and a 60 rocking joint connection between each of the carriers and the head.

4. In a train pipe connector a bracket adapted for attachment to a fixed train part, a pair of springs one above the other, each 65 connected at one end with said bracket, a pair

of carriers, one connected to the opposite end of each of said springs, a head supported by said carriers and spring-held connection joints between the head and the carriers affording movement therebetween. 70

5. In a train pipe connector, a bracket, a plurality of springs independently supported from said bracket, a plurality of carriers, one supported by each spring, a head and spring retained connection between the head 75 and carriers allowing angular movement between them, retracted by the springs.

6. In a train pipe connector, a head, a plurality of independently movable supports therefor and connections between the supports and the head comprising springs bearing 80 against the supports and bolts passing through the springs and supports and permitting the supports to rock upon the head, against the pressure of the springs. 85

7. In a train pipe connector, a head, a plurality of independently movable supports therefor and connections between the supports and the head comprising V-shaped joints between the supports and head, 90 springs bearing against the supports in the rear of the joints and bolts passing through the springs and head to hold the V-joints normally in contact but to permit rocking thereof. 95

8. In a train pipe connector, a head, a plurality of independently movable supports therefor and connections between the supports and the head comprising yokes upon the supports, blocks having V-shaped exterior surfaces carried by the yokes, cooperating contacts upon the head, one mating with each such V-shaped surface, bolts passing through the head and terminal blocks and springs compressed by the bolts lying 100 between the yoke members and bearing 105 against the supports within the yokes to maintain contact between the supports and head.

9. In a mount for automatic train connector heads, a head having a V-shaped, rearwardly facing rear portion adjacent each end of the head and supporting means for said head engaging these end portions of the head and held in engagement therewith 115 by spring compression.

10. In a mount for automatic connector heads, a head having a V-shaped, rearwardly facing rear portion adjacent each end of the head and supporting means for said head, 120 comprising a bracket, supports carried by the bracket, terminals of said supports cooperating with the head and adapted to rock thereon, springs bearing upon the rear of said terminals, and bolts passing through 125 the springs and compressing them against said terminals to cause retraction of the terminals against the head after rocking movement has taken place.

11. In a mount for automatic train con- 130

- necter heads, a head having a V-shaped rearwardly facing rear portion adjacent each end of the head and supporting means comprising a bracket and independently resiliently connected carriers for said head engaging the head at opposite ends thereof and spring-and-bolt retractive devices for these connections.
12. In a mount for automatic train connector heads, a head having a V-shaped rearwardly-facing rear portion adjacent each end of the head and supporting means for said head comprising a bracket, separate springs connected with said bracket, and connections between the springs and the rear portions of the head.
13. In a mount for automatic train connector heads, a head having a V-shaped rearwardly-facing portion adjacent each end of the head and supporting means for said head comprising a bracket, separate springs connected with said bracket, and connections between the springs and end portions of the head adapted to rock with respect to said head.
14. In a mount for automatic train connector heads, a head having a V-shaped rearwardly-facing rear portion adjacent each end of the head and supporting means for said head comprising a bracket having a plurality of split clamps, springs threaded into said split clamps and held therein, carriers mounted upon the opposite ends of said springs and connections between the carriers and the head.
15. In a mount for automatic train connector heads, a head having a V-shaped rearwardly-facing rear portion adjacent each end of the head and supporting means for said head comprising a bracket having a plurality of split clamps, springs threaded into the split clamps and held therein, carriers mounted upon the opposite ends of said springs and rocking connections between the carriers and the head.
16. In a mount for automatic train connector heads, a head having a V-shaped rearwardly-facing rear portion adjacent each end of the head and supporting means for said head comprising a bracket having a plurality of split clamps, springs threaded into the split clamps and held therein, carriers mounted upon the opposite ends of said springs and spring retracted slidable wedge connections between the carriers and the head.
17. In a mount for automatic train connector heads, a head having a V-shaped rearwardly-facing rear portion adjacent each end of the head and supporting means for said head comprising a bracket having a plurality of split clamps, springs threaded into the split clamps and held therein, carriers mounted upon the opposite ends of said springs and cylindrical spring retract-
- ed connection between the carriers and the head.
18. In a mount for automatic train connector heads, a head having a V-shaped rearwardly-facing rear portion adjacent each end of the head and supporting means for said head comprising a bracket having a plurality of split clamps, springs threaded into the split clamps and held therein, carriers mounted upon the opposite ends of said springs and conical, spring retracted connections between the carriers and the head.
19. In a mount for automatic train connector heads, a head having a V-shaped rearwardly-facing rear portion adjacent each end of the head and supporting means for said head comprising a bracket having a plurality of split clamps, springs threaded into the split clamps and held therein, carriers mounted upon the opposite ends of said springs and spring-retracted connections between the carriers and the head.
20. In an automatic train pipe connector, a bracket and head and connections between the upper and lower parts of said head and the bracket including separate springs sustaining the entire weight of the head.
21. A train pipe connector comprising a bracket, a pair of spaced springs connected therewith at one end, a head and separate spaced carriers for the head, one connected with each of said springs, the springs forming, between the carriers and the bracket, the sole support for the head.
22. In an automatic train connector, a head, separate carriers connected therewith resiliently, to rock thereon, a bracket and separate spring connections between the carriers and bracket.
23. In an automatic connector, a head, carriers therefor having wedge-faced connection with the head, springs and bolts resiliently uniting the carriers to the head, a bracket and spring support for said carriers from said bracket.
24. In an automatic train connector, a connector head, carrier terminals having wedge-faced engagement with said head, springs and bolts resiliently holding the terminals against the head, a bracket and connections between the carrier terminals and the bracket resiliently supporting the terminals.
25. In an automatic train pipe connector, a connector head, carrier terminals having wedge-faced engagement with said head, springs and bolts resiliently holding the terminals against the head, a bracket and connections between the carrier terminals and the bracket, resiliently supporting the terminals, the terminals being adapted to slide with respect to the head.
26. In an automatic train connector, a connector head, carrier terminals having

wedge-faced engagement with said head, springs and bolts resiliently holding the terminals against the head, and a bracket resiliently supporting the terminals, the terminals being adapted to slide with respect to the head and to rock thereon.

27. In an automatic train pipe connector, a head having wedge-shaped spaced rear faces, a pair of carriers having cooperating wedge-shaped faces engaging the rear of the head, springs engaging the carriers from the rear, bolts passing through the head and springs to normally hold the cooperating wedge-shaped faces in contact, a bracket and

independent mounts for the carriers from 15 the bracket.

28. In an automatic train pipe connector, a head having wedge-shaped spaced rear faces, a pair of carriers having cooperating wedge-shaped faces engaging the rear of 20 the head, springs engaging the carriers from the rear, bolts passing through the head and springs to normally hold the cooperating wedge-shaped faces in contact, a bracket and supporting springs for the carriers en- 25 gaging the bracket.

EDWARD A. ROBINSON.
